UNITED STATES PATENT OFFICE.

ORREN E. HINKLIN, OF MILFORD CENTRE, OHIO, ASSIGNOR, BY DIRECT AND MESNE ASSIGNMENTS, OF TWO-THIRDS TO ALBERT B. ROOTS, OF SAME PLACE, AND WALTER ALLEN, OF WASHINGTON, DISTRICT OF COLUMBIA.

WATCH-WINDING MECHANISM.

SPECIFICATION forming part of Letters Patent No. 296,170, dated April 1, 1884.

Application filed January 2, 1883. (No model.)

To all whom it may concern:

Be it known that I, ORREN E. HINKLIN, of Milford Centre, in the county of Union and State of Ohio, have invented a new and useful Improvement in Watches, of which the following is a specification.

My invention relates to a watch in which two mainspring-drums having cog-circles meshing with a pinion in a spur-wheel are employed.

The object of my invention is to so construct the winding department that the watch can be wound back and to the right hand, the defacement of the dial-plate being thus prevented; to locate all the winding and driving mechanism between the cap-plate, top plate, and the pillar-plate, so as to reduce the thickness of such a watch; to simplify the construction by making a single ratchet-wheel on the winding-arbor do duty for both mainsprings by being engaged by a single ratchet-pawl; to enable the watch to run longer; to provide a device capable of adaptation to stem-winding mechanism and to any escapement.

My improvement consists in the construction described hereinafter, and pointed out in the claim.

In order that my invention may be fully understood, I will proceed to describe it with reference to the accompanying drawings, in which—

Figure 1 is a rear view of a watch-movement embodying my invention. Fig. 2 is a similar view, from which portions of the housing-plate have been removed to expose the details of my winding mechanism. Fig. 3 is a section on the lines *x x*.

A is the front and B the rear plate of a watch-movement.

C is a shield or cap to protect and journal the two springs' pivots *d d'* and the winding-arbor *G*, and formed with recesses *e e'*, and *f*.

I employ two mainspring-drums, *D D'*, containing, respectively, two similar mainsprings, which, being of the customary construction, are not shown in the drawings. The shafts *d d'* of said springs have two precisely similar spur-wheels, *E E'*, occupying the recesses *e e'*, said spur-wheels both gearing into an intermediate wheel, *F*, occupying recess *f* of the cap, and upon the winding-arbor *G*.

The arbor *G* extends through the rear or pillar plate in the manner shown. A ratchet-pawl, *L*, engages a ratchet-wheel, *M*, on the arbor *G*. A spring, *N*, keeps the ratchet-pawl *L* in engagement with the ratchet-wheel. Each drum has a spur-wheel, as shown at *H* and *H'*, in the same plane, so as to engage the nearly - opposite sides of the intermediate pinion, *I*, mounted on whose shaft is a spur-wheel, *J*, that gears into the hour-hand pinion *K*. By this means I provide within the compass of an ordinary watch-movement and between the customary housing-plates two mainspring systems, which, being simultaneously wound by a single customary right-hand winding-arbor, both act on the train, and are capable of continuing it in motion for a week or other protracted period, depending on the aggregate strength of the springs. The interposition of an additional speed-wheel and pinion at least doubles the number of rotations of the hour-hand relatively to those of the spring-barrel, this of course imposing a greater labor on the spring, which is overcome by doubling the spring-power.

Having thus described my invention, the following is what I claim as new therein and desire to secure by Letters Patent:

In a watch, the combination of front plate, *A*, rear plate, *B*, shield or cap *C*, formed with recesses *e e'*, *f*, two mainsprings' drums, *D D'*, having spur-wheels *H H'* in the same plane, intermediate pinion, *I*, with which the drum spur-wheels engage, spur-wheel *J* on the intermediate pinion-shaft, hour-hand pinion engaged by the spur-wheel *J*, mainsprings' shafts *d d'*, journaled in the cap, spur-wheels *E E'* on the springs' shafts, occupying the recesses *e e'*, winding-arbor *G*, extending through the rear plate and cap, spur-wheel *F* on the arbor, occupying the recess *f* and meshing with the springs' spur-wheels *E E'*, a ratchet-wheel, *M*, on the arbor, and a spring ratchet-pawl to engage the ratchet, as set forth.

In testimony of which invention I hereunto set my hand.

ORREN E. HINKLIN.
